UNITED STATES PATENT OFFICE.

ALAN ROBB FERGUSSON, OF NEW YORK, N. Y., ASSIGNOR TO THE
FERGUSSON LOCK COMPANY, OF NEW JERSEY.

LOCK.

SPECIFICATION forming part of Letters Patent No. 643,955, dated February 20, 1900.

Application filed April 28, 1899. Serial No. 714,898. (No model.)

To all whom it may concern:

Be it known that I, ALAN ROBB FERGUSSON, a resident of New York city, in the county of New York and State of New York, have invented certain new and useful Improvements 5 in Locks; and I do hereby declare the following to be a full, clear, and exact description of the invention, such as will enable others skilled in the art to which it appertains to make and 10 use the same.

My invention relates to an improvement in locks, and more particularly to locks for mail-boxes and the like, the object of the invention being to provide a lock which it will be 15 practically impossible to "pick," in which the use of a spring-actuated bolt will be avoided, and which will be comparatively simple in construction, cheap to manufacture, neat in appearance, and most effectual when in use.

With this object in view the invention consists in certain novel features of construction and combinations and arrangements of parts, as will be more fully hereinafter described, and pointed out in the claims.

In the accompanying drawings, Figure 1 is a rear view illustrating my improvements. Fig. 2 is a sectional view of the lock, showing the normal position of the parts. Fig. 3 is a similar sectional view showing the positions 30 of the parts when the key is inserted. Fig. 4 is a longitudinal sectional view with the parts in their normal positions. Fig. 5 is a similar view with the key inserted. Fig. 6 is a view of the mail-box, showing my improved lock in place; and Figs. 7, 8, and 9 are views of details.

A represents the door of a mail-box, and B a casing for the parts of my improved lock, said casing being made integral with or 40 secured to the inner face of the door by brazing or otherwise. The sides of the casing are provided with laterally-projecting hollow enlargements 1 2, communicating with the interior of the casing, the enlargement 1 having an angular bore for the accommodation of the angular end 3 of the bolt 4 and the enlargement 2 having a circular bore for the reception of a revoluble sleeve 5, in which the cylindrical inner end of the bolt 4, projects, 45 and said sleeve is provided with a spiral slot 6, into which a pin 6^a on the bolt projects for

the purpose of causing a longitudinal movement of the bolt when the sleeve is turned, and thus cause the bolt to engage or be released from its keeper 8 when the sleeve 5 is 55 turned in one direction or the other. While the bolt can be readily manipulated by turning the sleeve 5, motion could not well be imparted to the sleeve by pressure applied to the end of the bolt, and hence the bolt could 60 not be worked back by means of an instrument inserted through the door or between the door and jamb. However, to insure against all possibility of the bolt being worked back one end of the slot 6 in the sleeve 5 may be offset slightly to form a shoulder 10, which will 65 constitute an abutment for the pin 6^a and constitute a positive lock for the bolt.

The inner end of the sleeve 5 is contracted, as shown at 7, and constitutes a support or 70 holder for my improved tumbler C and to which said tumbler is secured. The tumbler C is provided around its periphery with peculiarly-arranged projections 12, adapted to aline with and fit in recesses or cut-out portions 13 in a key 14, which will be more fully 75 hereinafter explained.

The tumbler C is provided on each side with peripheral grooves or recesses 15, in which are disposed lugs 16, projecting from 80 arms 17. The arms 17 are provided at their lower ends with holes or openings 18 for the reception of a shaft 19, on which said arms are loosely mounted. A double-coiled spring 20 is wound on the shaft 19 and is provided 85 at its ends with L-shaped arms 21, disposed in recesses 22 in the arms 17 and adapted to normally press the arms 17 against the tumbler C. The central portion of the spring 20 is disposed against a pin 23, which projects 90 through the shaft 19 and extends forward and bears against a plate or strip 24, pivoted to the casing and adapted to be pressed against the tumbler to prevent accidental displacement thereof.

The lugs 16, heretofore referred to, are adapted to strike against a projection 25 on the tumbler C when said tumbler is operated by other means than my improved key, as will now be explained. The upper ends of 100 the arms 17 are provided with enlargements 26, disposed in the path of the key and in

rear of the tumbler, so that as the key revolves the tumbler, before the projection 25 is engaged by the lug 16, the end of the key will push the arms 17 out of the way and permit the complete turning of the tumbler to withdraw the bolt. It will thus be seen that should unauthorized persons try to open the door without the aid of the key they would not be able to operate both the tumbler and 10 the arms simultaneously, and hence could not operate the lock.

My improved key 14 is preferably made concavo-convex in cross-section to conform to the shape of the tumbler, and the door is 15 provided with any approved spring-hinge 27 to open the door when the lock is unlocked.

It will also be seen that my improved lock is in no sense a spring-lock, and it is impossible to lock the door without the aid of the 20 key. In fact the key cannot possibly be withdrawn, leaving the lock in its unlocked position, as the mere withdrawing of the key will turn the tumbler and push the bolt forward to its locking position.

25 Various slight changes might be resorted to in the general form and arrangement of the several parts described without departing from the spirit and scope of my invention, and hence I would have it understood that I 30 do not wish to limit myself to the precise details set forth, but consider myself at liberty to make such slight changes and alterations as fairly fall within the spirit and scope of my invention.

35 Having fully described my invention, what I claim as new, and desire to secure by Letters Patent, is—

1. In a lock, the combination with a sliding bolt, of a tumbler adapted to turn thereon 40 and operate the same and means on the tumbler adapted to be engaged by a key movable tangentially to said tumbler.

2. In a lock, the combination with a sliding bolt, of a tumbler adapted to turn thereon 45 and operate the same and provided with a rack adapted to be engaged by a key movable tangentially to said tumbler.

3. In a lock, the combination of a sliding bolt and a tumbler mounted on the bolt and 50 adapted to turn thereon and transmit motion to the bolt, said tumbler having projections adapted to mesh with shoulders on a key movable tangentially to said tumbler.

4. In a lock, the combination of a revolvable tumbler having projections adapted to be 55 engaged by a key moved tangentially to the tumbler, a sleeve projecting from said tumbler and having a spiral groove, a bolt passing through the tumbler and a pin projecting 60 from the bolt and entering said spiral groove.

5. In a lock, the combination with a bolt and a revolvable tumbler for moving it, of means adapted to be actuated by the key after the tumbler has been partially turned for 65 releasing said tumbler to permit the complete withdrawal of the bolt.

6. In a lock, the combination with a bolt

and a revolvable tumbler adapted to operate said bolt, of a spring-actuated device adapted to prevent the full movement of the tumbler 70 and bolt and a key adapted to rotate the tumbler, move said device out of line therewith and effect the full withdrawal of the bolt.

7. In a lock, the combination of a bolt, a revolvable tumbler adapted to operate the bolt, 75 and a shoulder on said tumbler, of a spring-actuated arm having a portion normally in line with the shoulder on the tumbler and adapted to be moved out of line with said shoulder by a key after the tumbler shall 80 have been partially rotated.

8. In a lock, the combination of a bolt, a revolvable tumbler adapted to operate said bolt, and having shoulder, a series of independently-movable spring-pressed arms having portions in the path of said shoulder and a key constructed and adapted to rotate the tumbler and move said arms out of the path 85 of the shoulder thereon.

9. In a lock, the combination with a revolvable tumbler, of a locking-bolt adapted to be moved by said tumbler, an arm pivotally connected in proximity to the tumbler, a lug on the arm in the path of a projection on the tumbler and an enlargement on said arm in 95 the path of the key to be inserted so that when the key is inserted it will strike the enlargement on the arm and force the lug out of the path of the projection on the tumbler and permit the complete revolution thereof 100 to withdraw the bolt.

10. In a lock, the combination with a revolvable tumbler having peripheral projections and a key to rotate said tumbler by engagement with said peripheral projections, a bolt means 105 intermediate of the bolt and tumbler for converting the rotary motion of the tumbler into longitudinal movement of the bolt, means for arresting the tumbler before the complete withdrawal of the bolt and a key for rotating 110 the tumbler and actuating said arresting means to permit the complete movement of the tumbler.

11. In a lock, the combination of a tumbler, a key adapted to rotate said tumbler by engagement with the periphery thereof, pivoted arms adapted to arrest the rotation of the tumbler when the latter is rotated otherwise than by the key, said arms having portions normally in the path of the key and adapted 115 to be engaged by said key to move said arms away from the tumbler, a bolt and connections intermediate of the tumbler and bolt for moving the latter.

12. In a lock, the combination of a revolvable tumbler and a key adapted to rotate said tumbler, a spring bearing against the periphery of said tumbler to insure its retention in normal starting position, a bolt and connections between the bolt and tumbler.

13. In a lock, the combination of a tumbler having its peripheral face curved transversely, projections on said peripheral face, a bolt, connections between the tumbler and

bolt for operating the latter, spring-actuated devices adapted to arrest the tumbler and a key curved transversely to conform to the peripheral face of the tumbler and having 5 openings to receive the projections on said peripheral face when moved tangentially thereto to rotate the tumbler and move said spring-actuated devices away from the same.

14. In a lock, the combination of a tumbler, 10 a key adapted to rotate said tumbler by engagement with the peripheral face thereof, shoulders on the tumbler, two independently-movable arms having portions normally in line with said shoulders and also having portions in line with the keyway, a bolt and 15 means for transmitting motion from the tumbler to the bolt.

15. In a lock, the combination with a revolute tumbler having peripheral projections and a bolt actuated by said tumbler, of a pivoted arm adapted to arrest the tumbler, a shutter bearing against the tumbler to retain it in normal starting position, a spring serving to press the pivoted arm and the shutter toward the periphery of the tumbler and a 20 key for rotating the tumbler and moving said pivoted arm away from the same. 25

In testimony whereof I have signed this specification in the presence of two subscribing witnesses.

ALAN ROBB FERGUSSON.
